CRYSTALLIZATION APPARATUS

John A. Weedman, Bartlesville, Okla., assignor to
 Phillips Petroleum Company, a corporation of
 Delaware

Application August 22, 1949, Serial No. 111,618

10 Claims. (Cl. 23—273)

1

This invention relates to crystallization apparatus. In one aspect, it relates to an apparatus for the separation of mixtures by multi-stage crystallization. In another aspect, it relates to an apparatus for efficiently moving a granular mass of crystallized material through a fractional crystallizer.

In the separation of mixtures of compounds by fractional crystallization, various types of apparatus have been constructed for establishing contact between a mass of the crystallized material moving in one direction and a mother liquor moving in the opposite direction. Usually these devices employ a flight conveyor or auger for moving the crystals. In most horizontal type crystallizers, a higher-melting fraction is removed from one end, a lower-melting fraction is removed from the opposite end and the feed is introduced at an intermediate point. The apparatus may be jacketed to abstract heat through the walls and form crystals in the liquid body, which usually fills the apparatus. The crystals that form in contact with a mother liquor are, ordinarily, the higher-melting fraction. In the case of eutectic mixtures, the crystals may or may not be the higher-melting component but will be that component present in excess of the eutectic ratio.

One of the principal difficulties with the devices of the prior art is that the crystal movers are not efficient if the ratio of solid to liquid becomes too high. When the amount of solid material is too high, the flights of the conveyors bridge over with crystals and no crystal movement occurs. It is necessary, if separation is to occur, that the crystals or solid granular material be continuously moved toward the outlet for the higher-melting fraction and that the remaining liquor be displaced toward the opposite end, where the lower-melting fraction is withdrawn.

I have discovered a solid-moving device which operates efficiently in any slurry of crystals in liquid and which does not become bridged over with the material being crystallized. My invention is particularly adapted to use in a crystallizer that is totally enclosed and has a freezing section near one end and an adiabatic section through which the crystals must be moved before reaching the product outlet.

The principal object of my invention is to provide a simple and efficient apparatus for moving crystals through a liquid-full container and displacing liquid in the opposite direction.

Another object is to provide a conveyor for use in multi-stage crystallization apparatus.

Another object is to provide a crystal conveyor for moving the solids of a slurry to one end of the apparatus countercurrently to the liquid.

Other objects and advantages will be apparent

from a study of the following drawings, description and claims.

Figure 1 is a longitudinal sectional view of a horizontal type crystallizer showing my crystal conveyor in elevation.

Figure 2 is a cross sectional view of Figure 1 taken along line 2—2.

Figure 3 is a detailed view, part sectional and part elevational, taken along line 3—3 of Figure 2.

Figure 4 is a cross sectional view of a cylindrical crystallizer showing a modification of a crystal mover in elevation.

In Figure 1, a reciprocating rod 6 extends through the end wall of crystallizer 7 longitudinally into said crystallizer. Close-fitting pistons 8 are spaced along rod 6 and secured thereto. Stuffing box 9 seals the space around rod 6, which is caused to reciprocate by the movement of crank 11 and connecting rod 12, which are actuated by a driving means, not shown. A bar 13 is secured to rod 6 and extends transversely to form a stop for the foldable pistons 8. The reciprocating rod may be made up as a unit or it may be made up in sections which are joined together by means of couplings as shown at 14. Product outlets 16 and 17 are at opposite ends of the apparatus and feed inlet 18 is intermediate said ends. Cooling jacket 19 forms a freezing section on one end and heating jacket 21 forms a melting section on the opposite end. Cylinder 22 and piston 23 communicate with crystallizer 7 by means of a passageway 24 to make possible the maintenance of a desired pressure within said crystallizer.

In Figure 2, the cross sectional wall of crystallizer 7 is shown, inside of which is a collapsible piston which is made up of a close-fitting ring 26 which is secured to reciprocating rod 6 by means of vertically-extending spokes 27. A pair of semi-circular flaps 28 are loosely secured to said vertically-extending spokes by means of loops 29. Horizontal bar 13 serves to stop the folding of said flaps on the reverse stroke of the piston and stops 31 on the inner periphery of ring 26 stop the flaps at the fully opened position during the advance stroke.

In Figure 3, reciprocating rod 6 and vertical spokes 27 are shown positioned in a section of crystallizer 7. Flaps 28 are rotatably secured to vertical spokes 27 by means of loops 29. Stop 31 on ring 26 prevents rearward folding of said flaps.

In Figure 4, the perforate piston 32, which is secured to reciprocating rod 6, is provided with flaps 33 which close the large openings through said piston.

This device is designed for the purpose of moving a mass of granular solid through a confined body of the mother liquor, which is thereby displaced in the direction countercurrent to the movement of the crystals. This device eliminates the difficulty resulting from bridging across the

flights which usually occurs with augers or flight conveyors.

By using my apparatus, the crystals formed in the freezing zone are scraped from the walls by the rigid outer ring 25 and are pushed forward through the crystallizer by the perforate pistons. At the same time, liquid is displaced in the opposite direction and flows through the perforations in the piston. On the reverse stroke, the foldable flaps 28 fold forward to form an opening around the sides thereof of considerable size. These flaps are prevented from folding completely inward against the reciprocating rod by stop 33. This prevents the flaps from coming to rest on dead center and failing to open on the forward stroke. As the forward stroke begins, the resistance of the solid in the solution forces the flaps back against stops 34 and thereby forms a piston again.

The pistons of my device are entirely automatic and open and close freely with the motion of the reciprocating rod. My device is operable as long as the mixture in the crystallizer is maintained as a slurry. If the crystals are melted and a portion of the melt is caused to flow toward the freezing end as reflux, my device will be operable under conditions of complete reflux. If the crystals are not melted in the apparatus but are removed as solid material, it is obvious that this removal must occur at the same rate that the material is delivered to the end of the apparatus. Otherwise, there would be a building up of solid material in the end of the apparatus which could result in damage to the pistons. Then, as set forth hereinbefore, crystals resulting from movement through my apparatus can be melted in the melting section and the resulting melt removed through conduit 16 as a liquid, or the crystals can be partially melted and removed through conduit 16 as a slurry, or the crystals can be removed as such without melting them.

The perforate piston may be made of any foraminous material which will permit the flow of liquid therethrough without substantial resistance and at the same time will retain granular material. It does not effect the operation if some small crystals do pass through the piston along with the liquid. These crystals are probably impure and more closely approximate the composition of the liquid than do the larger crystals which are retained on the piston. I have found that a 20 to 30 mesh screen is excellent for this purpose.

The screen for the flaps is secured to a reinforcing ring which has loops or eyelets to fit around the vertically extending spokes. The screen may be secured to the reinforcing ring by any desired method but I have found soldering to be very convenient. The hinge action of the loops around said spokes must be easy so that the resistance required to open and close the flaps will be negligible.

Instead of stops 34, which are soldered to the periphery of the scraper ring 25, any other convenient method for preventing the backward folding of said flaps may be used.

In the drawings, my apparatus is shown in a horizontal position. However, it may be operated in a vertical or inclined position and in some instances, such positions may be preferable. In operating with the crystallizer full, or substantially full of slurry, the slurry would offer sufficient resistance to the foldable pistons to cause said pistons to unfold on the pump stroke and fold on the intake stroke. My apparatus is

not limited to operation at any certain pressure but is operable at constant or pulsating pressures ranging from subatmospheric to superatmospheric pressures. It is possible to use a feed comprising crystalline material. The operation of my apparatus is still the same. It is also possible to operate the apparatus in a non-horizontal position with the melting section at the elevated end.

The advantages of my invention will be more clearly understood from the following example.

EXAMPLE

The following tests were carried out to determine the maximum amount of high purity benzene to be obtained by crystallization from a benzene n-heptane feed in a crystallizer using first an auger-type conveyor, and then a porous piston-type conveyor, such as that shown in Figures 1, 2, and 3. The crystallizer tube was a 10 foot section of 2 inch tubing with a cooling jacket adjacent one end and a heater at the opposite end.

In the first tests, it was found that the auger conveyor would not operate if the amount of crystals in the mixture exceeded about 5 per cent of the mixture. The output of high-melting product (benzene) dropped off rapidly as the purity of the product increased. At 98 per cent purity, which is not high enough, the high-melting product was 1.6 volume per cent of the feed, which is a negligible quantity for such a process. From these results, it is obvious that the crystallizer was being operated at about the maximum output for the purity of the product.

With the porous piston conveyor, the purity of the high-melting product was appreciably higher than that obtained with the auger conveyor. The rate of output of the high-melting product increased as the feed rate was increased. Even at a 33.5 volume per cent output, the purity remained at 99 per cent, which is considerably better than the 98 per cent purity obtained at a 1.6 volume per cent output with the auger-type conveyor. It is believed that the output from the porous piston crystallizer could be increased even more without sacrificing purity of the product.

The data in the following table are the results of the tests just described. The advantages of my invention will be more clearly demonstrated and understood from a study of the following table.

Table
WITH AUGER

Feed	Low-Melting Product	Rates, ml./min.		Compositions, wt. percent Benzene		
		Rate	Vol. percent of feed	Feed	Low-Melting Product	High-Melting Product
3.08	2.64	0.44	14	46.4	14.5	75.3
2.77	2.51	0.28	9.0	46.2	14.0	87.5
6.3	6.0	0.3	4.8	59.5	18.5	90.0
6.1	6.0	0.1	1.6	56.2	24.5	98.0

WITH POROUS PISTONS

19.15	14.0	5.15	26.9	75.8	58.8	99.1
18.30	14.0	4.30	23.5	75.8	55.0	99.2
24.6	18.9	5.7	23.2	75.9	63.2	98.9
35.0	23.3	11.70	33.5	73.0	53.1	99.0

If desired, an indicator may be installed in connection with said flaps to indicate when the flaps are opening and closing properly. This would also indicate whether or not optimum operating conditions were being maintained since the flaps would fail to operate only in case the mixture inside the crystallizer became entirely liquid or the ratio of solid to liquid became too great. Such an indicating device is entirely within the scope of my invention, which is defined by the following claims.

Having described my invention, I claim:

1. A fractional crystallization apparatus which comprises, in combination, an elongated enclosed container, a product outlet adjacent each end of said container and a feed inlet intermediate said ends, means for adding heat to said container adjacent one end thereof, means for abstracting heat from said container along a portion thereof between said feed inlet and the unheated end, and means for moving solid granular material through said container from the cooled to the heated end which comprises a reciprocating rod extending axially into said container, a plurality of foldable pistons comprising foraminate members hinged at spaced intervals to said rod, said foldable pistons being adapted to close on the intake stroke and open on the pump stroke of said piston.

2. In a crystallizer of the type described comprising an elongated vessel having a first product outlet conduit in one end portion A of said vessel, a second product outlet conduit in a second end portion B of said vessel, a feed inlet conduit between said product outlet conduits and means for removing heat from said vessel between said feed inlet conduit and said end portion B, an improved solid-conveyor for moving solids toward end portion A which comprises, in combination, a reciprocating rod extending axially into said crystallizer, a plurality of foldable perforate pistons comprising a screen having a plurality of perforations disposed at spaced intervals along said rod and secured thereto, and means to prevent rearward folding of said pistons during the forward stroke of said rod.

3. In a crystallizer of the type described comprising an elongated vessel having a first product outlet conduit in one end portion A of said vessel, a second product outlet conduit in a second end portion B of said vessel, a feed inlet conduit between said product outlet conduits and means for removing heat from said vessel between said feed inlet conduit and said end portion B, an improved solid-conveyor for moving solids toward end portion A which comprises, in combination, a reciprocating rod extending from one end longitudinally into said crystallizer, a plurality of foldable, foraminate pistons disposed at spaced intervals along said rod and secured thereto, means to prevent rearward folding of said pistons during the pumping stroke of said pistons, a rigid band at the periphery of said pistons for scraping solidified material from the wall of said crystallizer and means for actuating said reciprocating rod.

4. In a crystallizer comprising an elongated container having product outlet conduit A and B in the end portions thereof, a feed inlet conduit between said outlet conduits, means for abstracting heat from a portion of said container between said outlet conduit B and said feed inlet conduit, means for adding heat to a portion of said container between said outlet conduit A and said

feed inlet conduit and means for moving solids therethrough toward outlet conduit A in countercurrent contact with a liquid, an improved crystal-conveyor which comprises, in combination, a reciprocating rod extending axially into said container, a plurality of perforate pistons comprising a screen having a plurality of perforations secured to said rods at spaced intervals, a plurality of openings through said piston, a corresponding plurality of hinged flaps covering said openings and adapted to open on the intake stroke to allow passage of solids through said openings and to close on the pumping stroke to move the solids through said container, and means to effect the reciprocation of said rod.

5. In a fractional crystallizer comprising an elongated container having product outlet conduits A and B in the end portions thereof, a feed inlet conduit between said outlet conduits, means for abstracting heat from a portion of said container between said outlet conduit B and said feed inlet conduit, means for adding heat to a portion of said container between said outlet conduit A and said feed inlet conduit and means for moving granular solids therethrough toward outlet conduit A in countercurrent contact with a liquid, an improved solid-conveyor which comprises, in combination, a reciprocating rod extending longitudinally into said container and parallel to the axis of said container, a plurality of pistons formed by paired, semi-circular, flaps comprising a screen having a plurality of perforations transversely disposed along said rod at spaced intervals and secured thereto, said flaps being hinged and rotatable, means to stop the rotation of said flaps at the transverse position on the forward stroke and means to stop said rotation at an angle less than 90 degrees from the transverse position on the return stroke.

6. In a crystallizer comprising an elongated cylindrical container having product outlet conduits A and B in the end portions thereof, a feed inlet conduit between said outlet conduits, means for abstracting heat from a portion of said container between said outlet conduit B and said feed inlet conduit, means for adding heat to a portion of said container between said outlet conduit A and said feed inlet conduit and a crystal-conveyor for moving crystals toward outlet conduit A, an improved conveyor which comprises, in combination, a reciprocating rod extending axially into said container, a plurality of perforate pistons which comprise rings transversely positioned within said cylinder at spaced intervals along said rod, spokes extending inwardly from said rings and secured to said rod, a pair of semi-circular foraminate flaps rotatably hinged to the spokes of each ring and adapted to assume a transverse position and close the openings within said ring, a boss on the inner periphery of each ring to stop the rotation of said flaps at the fully extended position, a forward stop for each pair of flaps which comprises a transverse, horizontal bar secured to said rod in front of the corresponding piston, and means to actuate said reciprocating rod.

7. In a cylindrical, multi-stage crystallizer having a product outlet in each end and a feed inlet intermediate said ends, an improved conveyor for moving granular solids through said crystallizer countercurrently to the liquid therein which comprises, in combination, a reciprocating rod extending axially into said crystallizer, a plurality of closely-fitting rings transversely positioned within said crystallizer at spaced intervals along

said rod and secured thereto by means of transverse bars extending outwardly from said rod, a corresponding plurality of paired, semi-circular, foraminous flaps rotatably secured along their non-circular edges to said transverse bars, means to stop said flaps at their fully extended position, and means to actuate said reciprocating rod.

8. In a fractional crystallizer which comprises an elongated container having product outlet conduits A and B in the end portions thereof, a feed inlet conduit between said outlet conduits, means for abstracting heat from a portion of said container between said outlet conduit B and said feed inlet conduit, means for adding heat to a portion of said container between said outlet conduit A and said feed inlet conduit and a crystal conveyor for moving crystals toward outlet conduit A, an improved conveyor which comprises a reciprocating rod extending axially into said container, a plurality of perforate, pistons comprising a screen having a plurality of perforations disposed along and foldably secured to said rod, means to stop the unfolding of said pistons at their fully extended position during the advance stroke of said rod, and means to actuate said rod.

9. In a multi-stage crystallizer comprising a cylinder having a product outlet in each end and a feed inlet intermediate said ends, an improved crystal conveyor which comprises, in combination, a reciprocating rod extending through said cylinder and parallel to the axis of said cylinder, a plurality of perforate pistons disposed along said rod and foldably secured thereto, said pistons comprising paired, semi-circular, foraminous members hinged to rotate about a common axis transverse to said rod, means to stop the rotation

of said hinged members about said axis at their fully opened position on the forward stroke of the rod, means to stop the rotation of said semi-circular members on the reverse stroke short of a dead-center position, and means to cause said rod to reciprocate.

10. A fractional crystallization apparatus which comprises in combination, an elongated enclosed container, a product outlet adjacent each end of said container and a feed inlet intermediate said ends, means for adding heat to said container adjacent one end thereof, means for abstracting heat from said container along a portion thereof between said feed inlet and the unheated end, and means for moving solid granular material through said container from the cooled to the heated end which comprises a reciprocating rod extending axially into said container, a plurality of perforate pistons secured to said rod at spaced intervals, each of said pistons comprising a plurality of perforate members adapted to open to permit passage of solids through said pistons and adapted to close so as to move solids through said container in the direction of the heated end.
